SHOE SEWING MACHINE

Edward Quinn, Malden, Mass., assignor to United Shoe Machinery Corporation, Flemington, N. J., a corporation of New Jersey

Application March 12, 1941, Serial No. 382,904

17 Claims. (Cl. 112—35)

The present invention relates to shoe sewing machines, and is herein disclosed as embodied in an inseam sewing machine of the general type having a curved hook needle and cooperating instrumentalities for forming a chainstitch, and adapted for sewing together the insole, upper and welt of a welt shoe. The illustrated machine is provided also with means for making a series of slashing cuts passing through the sewing rib comprised between the oppositely disposed stretches of thread forming the stitches of the seam.

It is a principal object of the invention to provide in a machine of this general description having a curved hook needle, a looper and a thread finger movable to supply slack thread to the needle, a novel means for guiding and positioning the thread which will cooperate with the needle, looper and thread finger in such a manner as will insure the proper functioning of the stitch forming mechanism during operation upon all classes of work, and will markedly improve the quality of the stitching produced with respect to uniformity, tightness and proper location along the margin of the shoe.

It is a further object of the invention to provide an inseam sewing machine of the general type described, and having mechanism for slashing the sewing rib, of which the stitch forming mechanism is particularly constructed and arranged to support and to control the thread during the forming of successive stitches in such a manner as to preclude any possibility that the thread may become caught in the slashed portions of the sewing rib.

Other objects of the invention are to improve the construction and arrangement of certain operating instrumentalities of an inseam sewing machine of this description, with particular reference to improvements in the mechanism for slashing the sewing rib.

With these and other objects in view as may hereinafter appear, a principal feature of the invention consists in the provision in a machine of the general type described having a curved hook needle, a looper and a thread finger movable to supply slack thread to the needle, of a stationary thread finger having a thread engaging surface extending substantially parallel to the sewing rib and substantially below the edge thereof, and crossing the plane of movement of the needle sufficiently above the path taken by the needle to avoid interference of the parts.

The several features of the invention consist also in the devices, combinations and arrange-

ment of parts hereinafter described and claimed, which together with the advantages to be obtained thereby will be readily understood by one skilled in the art from the following description taken in connection with the accompanying drawings, in which Fig. 1 is a view in right side elevation illustrating a portion of the sewing head of an inseam shoe sewing machine, only so much of the machine having been disclosed as is believed necessary to illustrate the connection of the present invention therewith; Fig. 2 is an enlarged detail view in front elevation illustrating the relative positions of the channel guide, looper, needle and the movable and stationary thread fingers at the limit of the loop drawing stroke of the movable thread finger; Fig. 3 is a plan view of the parts shown in Fig. 2; Fig. 4 is a detail view in right side elevation partly in section, illustrating particularly the construction and arrangement of applicant's stationary thread finger; Fig. 5 is a view in front elevation partly in section of the parts shown in Fig. 4; Fig. 6 is a view in right side elevation illustrating particularly an improved construction and arrangement of the mechanism for operating the slashing knife and the associated welt supporting member; Fig. 7 is an enlarged detail view of the welt slashing knife and welt supporting element shown in Fig. 6; Fig. 8 is a view in front elevation of the parts shown in Fig. 7; Fig. 9 is a sectional plan view taken on the line 9—9 of Fig. 7; and Fig. 10 is a sectional plan view taken on the line 10—10 of Fig. 7.

The machine disclosed in the drawings as illustrating in a preferred form the several features of the present invention, comprises a welt sewing machine for attaching the welt to the insole and associated upper, and is substantially identical in its construction and mode of operation with the machine disclosed in the patent to Eppler No. 1,108,560. The shoe operating devices of the machine include a curved hook needle 20, a needle guide 22, a looper 24, a take-up 26, an auxiliary take-up 28, and a thread finger 30 movable to supply slack thread to the needle, together with the work supporting and guiding devices including a back rest 32, a welt guide 34, and a channel guide 36. The present machine is also provided with a rib slashing knife 38 and an anvil support 40 cooperating therewith adapted for making a series of slashing cuts passing through the sewing rib and forming segmental portions thereof which are held together by the stitches of the seam. The rib slashing mechanism except as herein described is similar to that

illustrated in applicant's Patent No. 2,247,691, dated July 1, 1941, for machines for operating upon shoes.

In accordance with the present invention, applicant provides a stationary thread finger 42 which cooperates with the movable thread finger, as hereinafter more fully pointed out, to maintain a more accurate control of the thread during the stitch forming operation.

In accordance with the usual construction of these machines, the needle 20 is mounted on a needle segment 44 mounted to turn on a stationary bearing and externally supported in a raceway 46 on the machine frame. In the illustrated machine, the awl has been omitted. The channel guide 36 is movable in the line of feed to feed the work, and to this end is mounted on a feed slide generally indicated at 48 which is reciprocated in the line of feed by means of a cam actuated feed lever 50. The feed lever 50 is supported at its forward end to turn about a fixed pivot and is connected to move the feed slide through connections including a block 52 adjustably supported in a slotted portion of the lever 50 and arranged to engage in a guideway 54 formed in the bottom side of the feed slide 48. The needle segment 44 is actuated from the reciprocable needle lever generally indicated at 60 (Fig. 1) which is connected by means of a curved link 62 to a pivot pin 64 on the needle segment 44. The needle guide 22 is mounted on a pivot pin 65 to turn coaxially with the needle segment 44, and is positively actuated through connections which include a gear segment 66 rigidly secured to the pin 65, and a cam actuated lever 68 supported to turn on a pivot 70, and having formed at its forward end a gear segment 72 which meshes with the segment 66.

The thread finger 30 is pivotally supported for movement rearwardly to engage with and form a bight in the thread extending from the looper to the work, and then forwardly to give up the slack thread thus provided to the needle during its retracting stroke. The main take-up of the machine is of usual construction consisting of the take-up lever 26 which is cam actuated and has mounted thereon a thread truck 76. The auxiliary take-up consists of the auxiliary take-up lever 28 having a thread truck 78 mounted thereon. The auxiliary take-up lever 28 is pressed upon by a spring-actuated plunger 80. This plunger is mounted in a vertical guideway in the frame of the machine, and its upper end is acted upon by a coil spring 82 seated in a recess in the machine frame. The auxiliary take-up is thus spring-pressed, its upward movements being resisted by the tension of the spring 82. The thread indicated at 84, after passing over the tension wheel at the rear of the machine, passes over a guide truck 86, then under the truck 78 of the auxiliary take-up, and then over the truck 76 of the main take-up. The arrangement of these trucks is such that during the rising movement of the main take-up, the auxiliary take-up is moved upward, and during the falling movement of the main take-up, the auxiliary take-up is allowed to fall and maintain a tension on the thread determined by the strength of the spring 82 and the relative positions of the three trucks. The main take-up falls during the thread pulling movement to the thread finger, during the looping movements of the looper, and during the retracting stroke of the needle. In accordance with the usual practice to prevent the auxiliary take-up from stealing thread from the thread finger

33 during its loop delivery or forward stroke, and while the needle is making the first part of its retracting stroke, a stop 88 is provided to limit the forward movement of the auxiliary take-up, which stop is engaged by an adjustable abutment screw 90 mounted in the auxiliary take-up lever 28. The stop 88 and abutment screw 90 are so arranged with relation to the falling movement of the main take-up and the thread delivering stroke of the thread finger, that the falling movement of the auxiliary take-up must stop before the thread finger 30 begins its thread delivering stroke. Inasmuch as the construction and arrangement of the thread handling instrumentalities thus far described, is substantially that illustrated in the Eppeler patent above referred to, no further description or illustration thereof is believed necessary.

The rib slashing mechanism of the illustrated machine is generally similar to that illustrated and described in applicant's patent above referred to, comprising the rib slashing knife 38 which is mounted on a knife segment 92 supported to turn on a pivot 96 which is formed integrally with the needle guide 22 and is eccentric with relation to the needle guide pivot pin 65, and a cooperating anvil support 40 which is arranged to engage with and force the sewing rib outwardly against the thrust of the knife 38 which enters from the channel side of the work. The knife 38 is fixed in the line of feed, and is spaced a predetermined distance from that side of the needle remote from the completed stitches of the seam, so that the slashing cut will always be spaced a predetermined distance from the point of operation upon the shoe at which the needle is operated to engage with and draw a new loop of thread through the work. The knife is located to form its slashing cut close to the point at which the needle is operating through the work, so that when the work is fed, the cut will be transferred to the other side of the needle a maximum possible distance for any given stitch length adjustment of the feed mechanism. The operation of the knife 38 is timed with relation to the operation of the needle 20 and needle guide 22, so that the downward movement of the knife takes place during the retracting movement of the needle guide 22 and while the eccentric pivot 96 is moving rearwardly about the axis of rotation of the needle guide on the pivot pin 65.

In the illustrated construction, the knife 38 is mounted on the knife segment 92 in such a manner as to permit of adjustment which will compensate for wear and successive sharpenings of both the outer and anvil engaging knife edges. To this end the knife is slidably supported in a guideway 97 which is disposed at such an angle with respect to the pivot 65 that adjustment of the knife outwardly in the guideway will serve to locate both knife edges simultaneously in their proper operating positions. A clamping screw 98 threaded to the knife member 38 and arranged to extend through a slot 99 in the knife segment 92 serves to hold the knife 38 rigidly in adjusted position.

The anvil support 40 is constructed and arranged to move in timed relation to the knife, acting as the knife moves downwardly, first to move downwardly and rearwardly, and then forwardly, forcing the sewing rib outwardly against the thrust of the knife. During retracting movement of the knife, the anvil support 40 is again moved rearwardly and up to its raised inoperative position as shown, for example, in Fig. 1

of the drawings. With the improved construction herein illustrated, applicant's anvil support 40 is constructed and arranged to provide support for the sewing rib at both sides of the knife 38, being formed for this purpose with a relatively long supporting surface extending lengthwise of the sewing rib at each side of the point of application of the knife. As clearly shown, for example, in Fig. 6 of the drawings, the anvil support 40 moves downwardly between the work and the welt guide and engages the sewing rib above the welt guide 34, and also above the welt. A slot 100 is formed in the face of the anvil 40 to receive the knife 38 to insure the proper operation of the knife to cut completely through the sewing rib.

As in applicant's patent above referred to, the rib slashing knife 38 and anvil support 40 are positively driven from the main cam shaft of the machine by means of a cam lever 102 supported to turn on a pivot pin 104 and arranged for imparting an oscillatory driving movement to a knife actuating lever 106 supported on the shaft 104. The lever 106 is urged in a clockwise direction by means of a tension spring 108 toward a limiting position with respect to the cam lever 102 in which a lug 110 on the lever 106 is engaged against a lug 112 on the cam lever 102. During operation of the slashing knife, the actuating lever 106 is positively connected to move with the lever 102 by means of a latch connection comprising a latch 114 carried on a pivot pin 115 on the lever 106 for engagement with a pin 116 on the forward end of the cam lever 102. A small torsion spring 118 coiled about the pivot pin 115 for the latch 114 tends normally to maintain the latch in locking position.

In order to disconnect the knife actuating lever 106 from active operation, mechanism is provided which comprises a control lever 120 supported to turn on a stationary pivot 122, and provided at its upper end with a right angle slot 124 to receive a cam roller 126 mounted on one end of the pivot pin for the latch 114. For the rearward operative position of the control lever 120, the cam roll 126 will ride in the vertical portion of the slot 124, so that the knife actuating lever 106 is free to reciprocate with the cam lever 102 as shown, for example, in Fig. 6 of the drawings. Forward movement of the control lever 120 as the cam lever 102 and knife actuating lever 106 reach their limiting down position, will cause the cam roll 126 to ride rearwardly in the horizontal portion of the slot 124 to lock the knife actuating lever 106 in a locked inoperative position. The forward movement of the control lever 120 is arranged also to disconnect the latch 114 from the latch pin 116. The disengagement of the latch 114 is effected by the engagement of a pin 128 on the control lever 120 with the downwardly extending arm of the latch lever 114 which acts to swing the latch lever rearwardly to the disconnected position shown in Fig. 1, against the pressure of its spring 118. The operation of the control lever 120 is controlled through connections which may be assumed to include a knee lever (not shown), and a vertical link 130 which is connected at its upper end to a rearwardly extending arm 132 of the control lever 120.

The actuating lever 106 is connected to impart oscillatory movements to the knife 38 through a link 134 connected at its lower end by means of a pivot pin 136 to the knife segment, and at its upper end by means of a pin 138 to the actuating lever 106. In order to provide a convenient ad-

justment to determine the throw of the knife 38, the pin 138 is adjustably mounted in a slot 140 formed in the forward end of the lever 106.

The anvil support 40 is formed in the lower end of a vertically extending rod 142 which is slidably supported toward its lower end against the knuckle 144 at the lower end of the link 134 forming part of the pivotal connection with the knife segment. A guard plate 146 rigidly secured to the knuckle 144 serves to provide a lateral support for the rod 142. The rod 142 is pivotally connected at its upper end to one end of a lever 148 supported to turn on a fixed pivot 150. The lever arm 148 is connected by means of a link 152 to the adjustable pivot pin 138 on the knife actuating lever 106. An extensible coupling 154 in the link 152 provides means of adjustment of the limiting down position taken by the anvil support 40.

In the improved form of the rib slashing mechanism herein illustrated, applicant provides means for effecting an additional adjustment of the limiting down position taken by the anvil 40 against the sewing rib to adapt the mechanism for operation upon extreme types of work in which heavy stock is employed, which necessitates a considerably higher location of the anvil support 40 against the upper portion of the sewing rib. To this end the lever 148 is provided with two slots 156 and 158 which are adapted alternatively to receive a pivot pin 159 mounted on the lower end of the link 152. From an inspection of Fig. 1, it will readily be seen that the location of the pivot pin for the link 152 in the slot 156 will cause the anvil 40 to be located in a relatively higher position with relation to the sewing rib at the limit of its down movement. The contour of the cam surface 152 engaging the knuckle 144 is such as to provide a corresponding compensation of the forward and back position of the anvil support at the limit of its down stroke for each position of adjustment.

In the operation of an inseam sewing machine of the general type described, provided with means for slashing the sewing rib, difficulty has been encountered with the operation of the stitch forming mechanism to produce the uniform tight and accurately placed stitch required for inseam sewing. This difficulty is believed to be due in large part to the novel conditions encountered, in which the sewing rib is weakened by the slashing operation, and therefore does not provide the customary support for the thread during the operation of the movable thread finger to supply slack thread to the needle. It has been found also that there is some tendency for the thread when bent rearwardly across the sewing rib by the movement of the thread finger, to become caught in the slashed portions of the sewing rib, with resulting injury to the work. In accordance with a feature of the present invention, applicant provides a stationary thread finger which is located in the stitch receiving channel formed between the sewing rib and the sole, and cooperates with the several stitch forming instrumentalities including the curved hook needle, the movable thread finger and the looper to guide the thread clear of the work, to accurately measure the amount of thread taken and subsequently given up by the movable thread finger to the needle, and to accurately place the exposed portion of the thread extending between adjacent stitches of the seam in the base of the stitch receiving channel. While applicant is

aware that secondary thread fingers have previously been employed which cooperate with the usual thread finger to more accurately measure the amount of slack thread supplied to the needle, applicant in the present instance provides a new and more efficient cooperation of the stitch forming instrumentalities by virtue of the use of a stationary thread finger which is rigidly and permanently positioned within the stitch receiving channel.

The stationary thread finger 42 provided in accordance with the present invention, comprises a curved element which projects into the stitch receiving channel, and has the shank portion thereof located at that side of the sewing point toward the completed stitches of the seam. The finger 42 is provided with a thread engaging surface 170 which extends lengthwise of the channel and across the plane of movement of the curved hook needle 20, and sufficiently above the same to avoid interference with the needle. In order that the thread finger 42 may be properly located for operation of the machine upon all classes of work which may be presented thereto, provision is made for adjustment of the thread finger 42 transversely, vertically and longitudinally with respect to the stitch receiving channel at the sewing point. The thread engaging surface 170 takes the form of a curve so shaped as to engage at its lowest point with the thread portion extending from the work and to support the thread in a continued substantially straight line as it is drawn from the stitch receiving perforation through the work by the thread drawing movement of the thread finger 30.

As best shown in Figs. 4 and 5 of the drawings, the stationary thread finger 42 is secured by means of screws 172 to a support 174 which is mounted for forward and back adjustment upon a slideway 176 formed in the under side of a U-shaped bracket 178. A clamping screw 180 which extends through a slot 182 in the support 174, and is screw-threaded into the bracket 178, serves to secure the support 174 to the bracket 178 in the desired position of adjustment. The U-shaped bracket 178 is pivotally mounted on a bushing 184, and is rigidly clamped in the desired position of angular adjustment with relation thereto, by means of a clamping screw 186 which passes through the two arms of the U-shaped bracket and through an axial bore in the bushing 184. The bushing 184 is carried in a bearing formed in a bracket 188 which is secured by means of screws 190 to the front side of the sewing head 192. In order to provide an additional adjustment of the stationary thread finger 42 lengthwise of the stitch receiving channel, the bushing 184 is arranged for axial adjustment in its bearing, and is clamped rigidly in position by means of a clamping pin 194 having one side thereof flattened at 196 for engagement with a corresponding flat 198 in the bushing 184. The engaging flattened portions 196, 198 serve to key the bushing 184 against rotational movement in its bearing while permitting axial adjustment thereof. A nut 200 screw-threaded to the clamping pin 194 serves to clamp the bushing 184 rigidly in adjusted position.

The operation of the stitch forming mechanism including specifically applicant's stationary thread finger 42 will be described as follows: After the needle has reached the limit of its loop drawing stroke, and again starts downwardly through the work, the take-up 26 moves up-

wardly to its limiting raised position to pull in the previously formed loop against the shank of the needle and to draw off additional thread from the supply. The auxiliary take-up 28 is 5 simultaneously moved upwardly by the tension on the thread against the pressure of its spring. As the take-up starts its downward movement, the movable thread finger 30 starts to move rearwardly from the dot-and-dash position shown in 10 Fig. 3, to draw in a bight of slack thread, both legs thereof being bent over the thread engaging surface 170 of the stationary thread finger 42. The take-up continues to fall as the thread finger pulls in its bight of thread, and continues this 15 movement during the operation of the looper 24 to thread the needle, and during the subsequent retracting or loop drawing movement of the needle through the work. The thread finger 30 retains control of its bight of thread during the 20 operation of the looper 24, and thereafter gives up thread to the needle during its retracting movement. It will be noted that both legs of the bight of thread held by the thread finger 30, are at all times engaged against and controlled 25 by the thread engaging surface 170 of the stationary thread finger 42, insuring an extremely accurate control of the thread during this portion of the stitch forming operation. As the needle approaches the limit of its loop drawing stroke, the thread finger 30 will have been 30 returned to the dot-and-dash position of Fig. 3, so that the thread is released therefrom, and while still guided by the thread engaging surface 170 of the stationary thread finger 42, is drawn down tightly into the base of the stitch receiving channel.

From the foregoing description, it will readily be seen that the thread engaging surface 170 of applicant's stationary thread finger 42 operates at all times as a guide support for the thread extending from the work during the 40 operation of the movable thread finger 30 and looper 24, and also during the retracting stroke of the needle 20 to cause the thread while manipulated by these instrumentalities to be positively supported away from the work, and finally, to be positioned accurately in the base of the stitch receiving channel. In this manner, an extremely accurate handling of the thread by 45 the stitch forming mechanism is insured which is entirely unaffected by such variables as thickness or strength of the work portions to be held together by the stitching. Any tendency of the thread to become caught in the slashing cuts 50 formed in the sewing rib which might otherwise result from the bending of the thread over the sewing rib by the operation of the thread finger 30 is entirely eliminated. It will be noted that the thread engaging surface 170 of the stationary thread finger 42 supports the thread while being acted upon by the movable thread finger 30 and looper 24 substantially in line with the needle perforations through which the thread 55 is drawn, so that no lateral strains may be exerted by these elements upon the work. This feature is of advantage in that it permits of the formation of tight stitching in work composed of weak or inferior materials without danger of tearing or otherwise injuring the same. The 60 operation of the stitch forming mechanism is improved also in other respects, in that the support for the thread provided by the thread engaging surface 170, permits the thread portion extending over the surface 170 from the preceding 65 stitch to be pulled through more firmly by

the thread finger 30 during its rearward stroke to supply slack thread for the needle. The more accurate control of the amount of thread taken and subsequently given up by the movable thread finger 30 acting in cooperation with the stationary thread finger 42, has been found also to result in an improvement in the operation of the auxiliary take-up cooperating with the thread finger 30 and looper 24, in that the auxiliary take-up does not seat against its stop, but operates at all times against its spring tension; thus providing a more uniform control of the tensioning strains exerted upon the thread by the stitch forming mechanism, and also making for a much more quiet operation of the machine.

While applicant's improved construction and arrangement of the stitch forming mechanism including particularly the stationary thread finger 42 has been found of particular advantage in connection with an inseam sewing machine having mechanism for slashing the sewing rib, it will be understood that the invention is not limited to a machine having a rib slashing mechanism, but has proved itself to be equally advantageous as applied to inseam sewing machines not so equipped. It is also to be understood that the invention is not limited to the specific construction and arrangement of parts adapted for sewing a so-called "outside-chain," in which the needle enters the work from the outside, but may also be with advantage applied to a machine adapted for sewing a so-called "reverse chain," in which the needle enters the work from the inside, and emerges through the upper or superimposed welt.

The invention having been described, what is claimed is:

1. In an inseam chainstitch shoe sewing machine, the combination of a curved hook needle, a looper, a thread finger movable to supply slack thread to the needle, a stationary thread finger for guiding the thread portions extending from the work to the looper and needle while engaged by the movable thread finger, and having the thread engaging surface thereof located substantially in line with the stitch receiving perforations through the work, and means for supporting the stationary thread finger rigidly in position.

2. In an inseam chainstitch shoe sewing machine, the combination of a curved hook needle, a looper, a thread finger movable to supply slack thread to the needle, a stationary thread finger for guiding the thread portions extending from the work to the looper and needle while engaged by the movable thread finger, of which the thread engaging surface is located substantially in line with the stitch receiving perforations through the work and extends in a direction generally parallel to the seam at the point of operation and across the plane of movement of the needle, and means for supporting the stationary thread finger rigidly in position.

3. In an inseam chainstitch shoe sewing machine, the combination of a curved hook needle, a looper, a thread finger movable to supply slack thread to the needle, a stationary thread finger for guiding the thread portions extending from the work to the looper and needle while engaged by the movable thread finger, of which the thread engaging surface is located substantially in line with the stitch receiving perforations through the work, and extends in a direction generally parallel to the seam at the point of operation across the plane of movement of the

needle and above the path taken by the needle, and means for supporting the stationary thread finger rigidly in position.

4. In an inseam chainstitch shoe sewing machine, the combination of a curved hook needle, a looper, a thread finger movable to supply slack thread to the needle, a stationary thread finger for guiding the thread portions extending from the work to the looper and needle while engaged by the movable thread finger, and having the thread engaging surface thereof located substantially in line with the stitch receiving perforations through the work, means for supporting the stationary thread finger rigidly in position, including adjusting means arranged to permit adjustment of said position of the thread finger freely in a plane parallel to the plane of needle movement.

5. In an inseam chainstitch shoe sewing machine, the combination of a curved hook needle arranged to enter the work from the outside and to emerge within a stitch receiving channel, a channel guide, a looper, a thread finger movable to supply slack thread to the needle, a stationary thread finger for guiding the thread portions engaged by the movable thread finger and having the thread engaging surface thereof located within the stitch receiving channel substantially below the edge of the sewing rib, and means for supporting the stationary thread finger rigidly in position.

6. In an inseam chainstitch shoe sewing machine, the combination of a curved hook needle arranged to enter the work from the outside and to emerge within a stitch receiving channel, a channel guide, a looper, a thread finger movable to supply slack thread to the needle, a stationary thread finger for guiding the thread portions engaged by the movable thread finger and having the thread engaging surface thereof located within the stitch receiving channel substantially below the edge of the sewing rib, and means for supporting the stationary thread finger rigidly in position including adjusting means arranged to permit adjustment of the stationary thread finger longitudinally of and in a plane transverse to the stitch receiving channel at the sewing point.

7. In an inseam chainstitch shoe sewing machine, the combination of a curved hook needle arranged to enter the work from the outside and to emerge within a stitch receiving channel, a channel guide, a looper, a thread finger movable to supply slack thread to the needle, a stationary thread finger for guiding the thread portions engaged by the movable thread finger and having the thread engaging surface thereof located within the stitch receiving channel substantially below the edge of the sewing rib, and means for supporting the stationary thread finger rigidly in position comprising a stationary support, a bracket mounted thereon for adjustment in a plane substantially parallel to the plane of needle movement, and a thread finger supporting member mounted on the bracket for adjustment in relation to the bracket in said plane.

8. In an inseam chainstitch shoe sewing machine, the combination of a curved hook needle arranged to enter the work from the outside and to emerge within a stitch receiving channel, a channel guide, a looper, a thread finger movable to supply slack thread to the needle, a stationary thread finger for guiding the thread portions engaged by the movable thread finger and having the thread engaging surface thereof located

within the stitch receiving channel substantially below the edge of the sewing rib, and means for supporting the stationary thread finger rigidly in position including a bracket pivoted for swinging adjustment in a plane substantially parallel to the plane of movement of the needle, and a thread finger supporting arm adjustably supported on the bracket.

9. In an inseam chainstitch shoe sewing machine, the combination of a curved hook needle arranged to enter the work from the outside and to emerge within a stitch receiving channel, a channel guide, a looper, a thread finger movable to supply slack thread to the needle, a stationary thread finger for guiding the thread portions engaged by the movable thread finger and having the thread engaging surface thereof located within the stitch receiving channel substantially below the edge of the sewing rib, and means for supporting the stationary thread finger rigidly in position including a bracket pivoted for swinging adjustment in a plane substantially parallel to the plane of movement of the needle, an axially adjustable pivotal support for said bracket, and a thread finger supporting arm slidably mounted on the bracket for further adjustment of the stationary thread finger in said plane.

10. In a chainstitch shoe sewing machine, the combination of a curved hook needle arranged to enter the work from the outside and to emerge within a stitch receiving channel, a looper, a thread finger movable to supply slack thread to the needle, and a stationary thread finger for guiding the thread portions engaged by the movable thread finger, having the thread engaging surface thereof located within the stitch receiving channel substantially below the edge of the sewing rib, and above the path taken by the needle, and crossing the plane of movement of the needle.

11. In an inseam chainstitch shoe sewing machine, the combination of a curved hook needle arranged to enter the work from the outside and to emerge within a stitch receiving channel, a channel guide arranged on that side of the needle remote from the completed stitches of the seam, a looper, a thread finger movable to supply slack thread to the needle, and a stationary thread finger cooperating therewith including a supporting shank located at that side of the needle opposite the channel guide, and having the thread engaging surface thereof located within the stitch receiving channel substantially below the edge of the sewing rib and above the path taken by the needle, and crossing the plane of movement of the needle.

12. In an inseam chainstitch shoe sewing machine, the combination of a curved hook needle arranged to enter the work from the outside and to emerge within a stitch receiving channel, a channel guide, a slashing knife arranged for making transverse cuts through the sewing rib, a looper, a thread finger movable to supply slack thread to the needle, and a stationary thread finger having the thread engaging surface thereof located within the stitch receiving channel substantially below the edge of the sewing rib.

13. In an inseam shoe sewing machine having stitch forming devices and slashing means acting in timed relation thereto for forming slashing cuts extending through the sewing rib, the combination of a curved hook needle arranged to enter the work from the outside and to emerge within a stitch receiving channel, a looper, a

thread finger movable to supply slack thread to the needle, and a stationary thread finger located within the stitch receiving channel for guiding the thread acted upon by the movable thread finger clear of the slashed sewing rib.

5. 14. In an inseam shoe sewing machine having stitch forming devices and slashing means acting in timed relation thereto for forming slashing cuts through the sewing rib, the combination of a curved hook needle arranged to enter the work from the outside and to emerge within a stitch receiving channel, a knife arranged to operate at that side of the needle remote from the completed stitches of the seam for forming slashing cuts in the sewing rib, a looper, a thread finger movable to supply slack thread to the needle, and a stationary thread finger located within the stitch receiving channel substantially at that side of the needle opposite from the knife for guiding the thread acted upon by the movable thread finger clear of the slashed sewing rib.

10. 15. In an inseam shoe sewing machine, the combination of a curved hook needle arranged to enter the work from the outside and to emerge within a stitch receiving channel, a channel guide, a looper, a thread finger movable to supply slack thread to the needle, a slashing knife arranged for making transverse cuts through the sewing rib, an anvil support having a knife receiving notch and substantial supporting surfaces at each side thereof to support portions of the sewing rib at both sides of the path of movement of the knife against the cutting stroke, actuating means for positioning the anvil support against the sewing rib substantially above the path followed by the needle in its work piercing stroke, and a stationary thread finger of which the thread engaging surface is located substantially in line with the stitch receiving perforations through the work, and extending in a direction parallel to the seam at the point of operation and across the plane of the needle.

15. 16. In an inseam sewing machine having stitch forming and work feeding devices, the combination of a slashing knife arranged for making transverse cuts through the sewing rib, and an anvil support having a knife receiving notch and substantial supporting surfaces at each side thereof for engagement with the sewing rib substantially above the path followed by the needle in its work piercing stroke for supporting the sewing rib against the cutting stroke of the knife.

20. 17. In an inseam sewing machine having stitch forming and work feeding devices, the combination of a slashing knife arranged for making transverse cuts through the sewing rib, an anvil support having a knife receiving notch and substantial supporting surfaces at each side thereof for engagement with the sewing rib substantially above the path followed by the needle in its work piercing stroke for supporting the sewing rib against the cutting stroke of the knife, and actuating means for moving the anvil support into and out of operative position, said means including a driving element, a link reciprocated thereby between fixed limits, a lever connected to move the anvil support to and from the work, and means for adjusting the limiting position of the support toward the work comprising a pin pivotally connected with the link and a slot in the lever in which the pin is adjustably secured.
